(57) **CLAIM**

The ornamental design for a breast pump funnel, as shown and described.

DESCRIPTION

FIG. 1 is a top, front, left side perspective view of a breast pump funnel, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear, right side perspective view thereof.

In the drawings, the broken lines are for the purpose of illustrating portions of the breast pump funnel that form no part of the claimed design.
